MARINE STERN LIGHT

John V. Hansen, Madison, and Ralph T. Jacobsen, Stoughton, Wis., assignors to The Electric Storage Battery Company, Philadelphia, Pa., a corporation of New Jersey

Filed May 15, 1961, Ser. No. 65,182

Term of patent 14 years

(Cl. D48—32)

FIG. 1 is an elevation of a marine stern light showing our new design.

FIG. 2 is an enlarged elevation thereof with the standard fragmentarily shown for convenience of illustration only.

FIG. 3 is a top plan view thereof.

FIG. 4 is a partial section taken along line 4-4 of FIG. 3.

The side of the marine stern light not shown is identical to that shown.

We claim:

The ornamental design for a marine stern light, as shown and described.
